UNITED STATES PATENT OFFICE.

MAXIMILIAN WENDORF, OF FRANKFORT-ON-THE-MAIN, GERMANY, AS-SIGNOR OF TWO-THIRDS TO ALBERT MEYENBERG AND SIEGMUND HENLEIN, OF SAME PLACE.

INCANDESCENT LAMP.

SPECIFICATION forming part of Letters Patent No. 592,851, dated November 2, 1897.

Application filed December 23, 1895. Serial No. 573,121. (No model.)

To all whom it may concern:

Be it known that I, MAXIMILIAN WENDORF, mechanic, of Frankfort-on-the-Main, Prussia, Germany, have invented new and useful Improvements in Incandescent Lamps, of which the following is a specification.

The object of my invention is to provide an oil-lamp by which a flame can be produced capable of making an incandescent body 10 glow as the Welsbach incandescent gas-light does; and said invention consists in the novel arrangement and combination of parts hereinafter described and claimed. For this purpose it is necessary to vaporize thoroughly 15 the oil, petroleum, hydrocarbons, alcohol, or the like, and to mix it with air in order to get a hot non-sooting flame of about blue color when coal-oil is used. By my invention the heat necessary for this evaporation is yielded 20 at the beginning of the operation by another flame to heat the evaporator. For this purpose there are means provided to vaporize benzine, gasoline, alcohol, or the like by a current of air blown through the liquid.

25 Further, my invention consists in the various means for generating the two flames above mentioned and in the details of construction hereinafter shown and claimed.

In order that my invention may be better understood, I make reference to the annexed drawings, showing an embodiment of my invention, wherein—

Figure 1 is a vertical section through the lamp. Fig. 2 is a side view of a part of it. 35 Figs. 3, 4, and 5 are detail sectional views of the cock on an enlarged scale.

C is the hollow perforated base of the lamp; A, the oil-tank; B, the benzine-tank, located in the interior of the oil-tank.

40 H is a rubber ball placed inside the lamp-base and communicating with the tank B by a pipe h. This pipe communicates with a branch pipe h', having a non-return valve h² and being adapted to be connected with a rubber ball H', which is used as an air-pump.

The pipe h terminates inside another larger pipe b', closed at the upper end by the wall or partition b².

45 The tank B is filled with cotton-battening and provided with a perforated wall or par-

tition B'. The tank B is fed with benzine by a pipe b, extending from the bottom of the tank B to the mouthpiece K. This serves also for the inlet of the oil to the tank A and is closed by a cover L. This cover is provided with a conical valve or stopper Z, which fits into the orifice of the pipe b and prevents the oil from overflowing if the lamp is inclined, but allows of a communication of compressed air between the tank B and tank A. The continuation b³ of the pipe b' communicates with the space above the partition B' by means of perforations x and also with the benzine-pipe a'.

The pipe a is filled with a wick, cotton, or the like, to filter the oil rising from the bottom of the tank A through said pipe. The casing M and the plug M' of the cock have two ports corresponding to the pipes a and a' and leading to the pipes m m', respectively. 65 The ports f and f' are so arranged in the plug M that when the port f' is turned to almost shut off communication between the pipes a' and m' the port f will be opened to establish communication between pipes a and m. There 70 are narrow grooves g g on the plug adjoining the openings of the port f, which allow a more delicate regulation than the wide orifice forming the port itself does. There is a scale N', which indicates whether the benzine-conduit 75 alone is open: first, when both conduits are open simultaneously; second, when the oil-conduit alone is open, and, third, when both conduits are closed, (o,) and thus the indications on the scale allow the regulation of the 80 oil-flow.

On the tank A are standards D, supporting the vaulted plate G' and surrounded by the cylinder G, of sheet metal. The plate G' is fixed to a tube P, which supports the burner. 90 The burner consists of the bracket E, into which the glass chimney F' fits, and of the evaporator R, which is fed with oil from below by the pipe m and which discharges the evaporated oil downward by a pipe p with a 95 nozzle p'.

The evaporator is placed in the enlarged head P' of the tube P by three arms r, which rest on the upper edge of a perforated cone t.

Under the cone t is an annular space T for 100

distributing the benzin-vapors entering by the pipe m' .

Q is a cap with apertures q placed on the lower end of the pipe P for admitting air to the vapors discharged by the nozzle p' and receives such small quantities of condensed oil as may drop.

u is a wire net of conical shape.

s is a pin on which the incandescent mantle S is hung.

The lower part of the glass cylinder F' is made conoidal, according to the customary shape of the mantle, whereas the upper part is cylindrical, as usual.

15 The operation and working of the new lamp are as follows: If the lamp is to be lighted, the hand N is set on number "1" of the scale N', and thereby the port f' opens communication between the pipes $a' m'$. Then by pressing

20 the ball II' the ball II is inflated and air driven through the pipes h and l' and through the benzin in the tank B. Benzin-vapors mixed with air pass through the pipes a' and m' into the annular chamber T and through the per-

25 perforated cone t to the wire net u . If a match is held to the top of the cylinder F', the vapors are ignited and an annular flame generated above the net-wire u . If this flame has burned a quarter or half a minute, the

30 evaporator is sufficiently heated, the hand N is turned to number "2," which establishes communication between the pipes $a m$, whereas communication between the pipes $a' m'$ is almost closed. The oil under the pressure

35 of the air enters the evaporator R, the under part of which is below the flame. The evaporator R is made of such size and the walls are sufficiently thin that it receives a sufficient amount of heat by the flame over u to vapo-

40 rize completely all the delivered oil. The vapors are conveyed from the upper end of the evaporator by the pipe p , which runs downward and ends in an upward-turned nozzle p' . Here the vapors are discharged and mixed

45 with air and delivered at the wire net u . Here they are ignited by the benzin-flame. Now the hand N is turned on to number "3" or some other place near it to which the lamp is regulated, whereby the benzin-inlet is cut

50 off and the oil-inlet is opened to the right extent. If necessary, the ball II' is worked now a little more to fill perfectly the ball II, the contents of which are sufficient to run the lamp for many hours, whereas the operation

55 of the benzin-flame necessitates a comparatively great amount of air.

The shape of the lower part of the chimney F' assists in preventing any obnoxious odor and provides a regular ignition of the products of combustion throughout the entire extent of the stocking, whereas the other devices have for their object the generation of a hot, blue, steady, and non-sooting flame. If the flame is to be extinguished, the hand

65 is turned to "1." Thereby the oil is cut off and the benzin-flame lighted for the purpose of preventing any soot being had by the slow

extinguishing of the oil-flame and to heat the evaporator R to the evaporation of the last particle of oil remaining in it.

The object of my invention is not restricted to the forms and instrumentalities above described; but

What I claim, and desire to secure by Letters Patent, is the following:

1. In an incandescent lamp the combination with a burner-head, of an evaporator contained therein, of a vapor-pipe communicating with the evaporator and having its discharge-opening under the burner-head, and a separate conduit connected with said burner-head and having a discharge-opening under the burner-head thereby providing an auxiliary burner for heating the evaporator, substantially as described. 75 80 85

2. In an incandescent lamp, the combination with two tanks for a burning and an igniting fluid, of pipes leading to the burner-head, and means to shut or open both pipes or either of them, substantially as described. 90

3. In an incandescent lamp, the combination of two tanks for a burning and an igniting fluid, of pipes leading from them to the burner-head, and of means to open the igniting-pipe, open the lighting-pipe and close the igniting-pipe consecutively by one handle, substantially as described. 95

4. In an incandescent lamp, the combination with two tanks for the burning and the igniting fluid, of means to set both tanks under atmospheric pressure, and of means to store up the compressed air and delivering it, substantially as described. 100

5. In an incandescent lamp, the combination with a burner-head and means for feeding the same, of auxiliary means for feeding, from a tank independent of the main tank or reservoir, an easily-evaporating fluid, as benzin or alcohol, means for forcing air through the fluid in said independent tank to the burner-head, substantially as described. 105 110

6. In an incandescent lamp, the combination of a burner-head, of an igniting device consisting of a tank independent of the main tank or reservoir containing cotton or the like, and an easily-evaporable fluid, an air-pump communicating with said independent tank, an air-pipe opening at the bottom of the tank, and a discharge-pipe at the cover of the tank, substantially as described. 115 120

7. In an incandescent lamp, the combination with a hollow burner of two basins or tanks for a burning and an igniting fluid, of means to set both tanks under pressure, of pipes extending from the said tanks and communicating with the inner space of the burner, and of means to open or close the said pipes together or alternatively substantially as described. 125

8. In an incandescent lamp, the combination with an oil-tank, of a benzin-tank, of pipes extending from the tanks to the burner, of a rubber ball, a pipe extending from the rubber ball and communicating with the said

tanks, means to fill the said ball with compressed air, and means to open or close the said tank-pipes, substantially as described.

9. A burner for an incandescent lamp consisting of an open pipe ending in an enlarged perforated burner-head, an evaporator placed at the top of the burner and heated thereby, a pipe leading to the evaporator, a second pipe leading from the top of the evaporator downward and ending in an upward-turned nozzle, a pipe for the supply of the igniting agent, and means to discharge the igniting agent within said burner-head, substantially as described.

10. In an incandescent lamp the combination with an oil-tank of a benzin-tank, a hollow foot, a rubber ball placed inside the hollow foot, means to inflate the ball, communicating passages between the ball and the said tanks, a double-passage cock at the top of the oil-tank, a burner supported by the said tank, pipes connecting the cock with the tanks and the burner, and a scale for indicating the position of the cock, substantially as described.

11. In an incandescent lamp the combination with an oil-tank and a benzin-tank, of a mouthpiece in the oil-tank, a filling-pipe of the benzin-tank extending into the said mouthpiece, and means to close the mouth-

piece substantially as described.

12. In an incandescent lamp the combination with a burner-head, of an oil-tank, a pipe opening near the bottom of said tank and communicating with the burner-head, filtering filling in the pipe, an independent pipe also communicating with the burner-head and a

single cock controlling the communication of said pipes with the burner-head, substantially as described.

13. In an incandescent lamp the combination with an oil-tank of a benzin-tank placed in it, a cotton filling in the benzin-tank, a false perforated plate under the cover of the latter tank, a pipe extending from the top of the tank to the burner, a pipe communicating with a compression air-reservoir and extending upward in the benzin-tank, a larger pipe closed at the top and open at the bottom and surrounding the said pipe, and a pipe extending from the benzin-tank into the oil-tank and opening near the top of it, substantially as described.

14. In an oil-lamp, the combination of an expansible reservoir, means auxiliary thereof for supplying pressure thereto, an oil-tank and benzin-tank in communication with said expansible reservoir, a burner connected by suitable pipes to said oil and benzin tank and means to regulate the flow of igniting and burning fluid to said burner.

15. In an oil-lamp, the combination of a single burner-head and means for supplying the said burner-head, first with an igniting fluid from one tank and then with a burning fluid from a second tank.

In testimony whereof I have signed my name to this specification in the presence of two subscribing witnesses.

MAXIMILIAN WENDORF.
